UNITED STATES PATENT OFFICE.

FRANZ CECKA, OF CHEMNITZ, GERMANY, ASSIGNOR TO THE FIRM OF SCHUBERT & SALZER MASCHINENFABRIK AKTIENGESELLSCHAFT, OF CHEMNITZ, GERMANY.

APPARATUS FOR MAKING REINFORCED KNITTED GOODS.

1,213,338.

Specification of Letters Patent.

Patented Jan. 23, 1917.

Application filed July 22, 1914. Serial No. 852,416.

To all whom it may concern:

Be it known that I, FRANZ CECKA, a citizen of the German Empire, residing at Chemnitz, in the Kingdom of Saxony, Germany, have 5 invented certain new and useful Improvements in Apparatus for Making Reinforced Knitted Goods; and I do hereby declare the following to be a full, clear, and exact description of the invention, such as will enable others skilled in the art to which it 10 appertains to make and use the same, reference being had to the accompanying drawings, and to letters or figures of reference marked thereon, which form a part of this specification.

15 My invention relates to improvements in a method of and apparatus for making reinforced knitted goods.

20 In the manufacture of knitted goods it is usual to loosen the loops when making reinforced parts, in order to impart sufficient elasticity to the reinforced parts. If the reinforced parts were made with the same close loops as the parts which are not reinforced, the goods would be close and 25 unelastic in the reinforced parts.

25 In order to loosen the loops the knitting depth of the frame is increased by rocking the needle bar so as to produce loops of increased length, for which purpose the known 30 loosening and closing cam is set at the beginning of the operation so as to produce for a definite part of the aggregate stroke of the thread guide a different knitting 35 depth.

35 The object of the improvements is to provide a method of and an apparatus for knitting reinforced goods by means of which fashioned reinforced parts can be produced, 40 i. e. reinforced parts which are of varying breadth.

45 With this object in view my invention consists in the matters to be described herein-after, and particularly pointed out in the appended claims, reference being had to the accompanying drawings and to the letters of reference marked thereon.

50 In said drawings Figure 1 is a diagrammatical view showing a knitting apparatus of known construction, Fig. 1^a, is a perspective view of the mechanism for actuating the needle bar. Figs. 2 and 3 are diagrammatical views showing respectively reinforced heel and toe portions of a knitted stocking 55 prior to uniting the sides of the same, the

reinforced portions having the forms now in use, Figs. 4 and 5, are similar views showing goods in which the reinforced portions are made according to my improved method, Fig. 6, is a view of a mechanism suitable for 60 making reinforced goods according to my improved method, and Figs. 7 and 8, are cross-sections taken respectively on the lines A—B and C—D of Fig. 6.

The same letters of reference have been 65 used in all the views to indicate corresponding parts.

Referring to Figs. 2 and 3, in the manufacture of the cross-hatched parts F of the heel and S of the toe the length of the loops 70 is increased over the whole breadth of the head of the frame. However, if it is desired to make a reinforced ankle H, as is shown in Fig. 2, or a double sole D, as is shown in Fig. 3, a part only of the breadth 75 a—b and a'—b' of the blank is reinforced, i. e. the portions a—c and d—b and a'—c' and d'—b', while the portions c—d and c'—d' are not reinforced. In such cases the knitting depth is temporarily varied by 80 pressing the needle bar N from the position I into the position II, so as to increase the length of the loops. This is done by means of cams 8 and 10, mounted on a shaft 1. As the distance z of the said cams 8—10 is 85 constant, the border lines 1—2 and 1'—2' of such reinforced portions are straight, as is shown in Figs. 2 and 3. The breadth c—d and c'—d' between the reinforced portions 90 can be set before the operation, but it can not be changed in the course of the manufacture of the goods. The border lines of the reinforced parts are always made by the same needles of the head of the frame.

95 While for the proper comprehension of the object of the present invention the diagrammatical showing of the operating connection of the needle bar N, as given in Fig. 1, is obviously sufficient, the real relation of the parts and their proper co-operation may be ascertained by reference to Fig. 1^a, in which 100 41 designates the ordinary actuating cam for the needle bar N. The cam 41 is secured upon the shaft 1 and controls a bowl 42 carried by an arm 52 which with its shaft 47, is mounted to be able to oscillate. The needle bar N is adapted to swing on the pivots 45 and about the shaft 46, and is operatively connected to the said rocking arm 52 by 105 means of links 43 and 44. If the actuating 110

cam 41 moves the bowl 42 radially outward, the rocking arm 52 will thereupon cause the needle bar N to swing toward the presser bar P as indicated by the arrow II. Upon 5 the said shaft 1 there are mounted the cams 8 and 10 above described as producing the required additional movements of the needle bar for temporarily increasing the length of the loops to be formed. For this purpose 10 the cams 8 and 10 are adapted to coöperate with a bowl 49' carried at the end of an arm 49, which is secured upon a rocking shaft 50. The latter shaft 50 is provided with a second arm 51 adapted to engage an extension 52' of the arm 52 controlling the operation 15 of the needle bar N.

When by any suitable means the bowl 49' is shifted into the path of action of the loop 20 loosening cams 8 and 10, the needle bar N will then be controlled by the said loop loosening cams 8 and 10 and moved according 25 to the extent of the strokes of the latter.

By means of apparatus of this class such 25 reinforced goods can not be made which are provided with fashioned reinforced portions, such as are shown for example in Figs. 4 and 5, where not only the breadth, but also the inner border lines of the reinforced portions are changed and made by 30 different needles. Therefore the apparatus can be used only in such cases in which a reinforced portion is to be produced which begins in definite rows of loops and which is not changed in the course of the operation. But where fashioned reinforced portions 35 are to be made in which the breadth is increased or reduced in the course of the manufacture the apparatus can not be used.

In order to obtain a variation of the knitting 40 depth which corresponds to the desired form of the reinforced portions the cams of the loosening and straightening cam are so mounted relatively to each other that their relative position can automatically be changed while the machine is in operation, so that the effect of the cams and the setting 45 of the needle bar caused thereby and the variation of the knitting depth can be performed in the successive rows of loops at different points. Thereby I am enabled to produce reinforced portions which are gradually increased or reduced, such as is shown by way of example in Figs. 4 and 5. The 50 cams are set in a suitable way by means of a jacquard card or a counting mechanism according to the desired form of the reinforced parts. Thereby I am also enabled to produce reinforced portions of uniform breadths in narrowed or widened goods.

In order that my invention be more clearly 60 understood mechanism for putting the same into effect has been shown by way of example in Figs. 6 to 8. As shown in the said figures, a shaft 1 carries a disk 2 the hub 3 65 of which provides a loose support for disks

4 and 5 which are held in position by means of a washer 6. The disk 4 is provided with rack teeth 7 and it is made integral with a cam 8, and the disk 5 is formed with rack teeth 9 and is provided with a cam 10. In 70 bores made in the disk 2 two shafts 11 and 12 are mounted. On the shaft 11 and at one side of the disk 2 a gear wheel 13 is mounted which is in mesh with the rack teeth 7, and at the opposite side of the disk 75 2 a gear wheel 14 and a ratchet wheel 15 are secured to the shaft 11.

To the shaft 12 a gear wheel 16 and at the opposite side of the disk 2 a gear wheel 17 and a ratchet wheel 18 are secured. The 80 gear wheels 14 and 17 are in mesh with each other.

On a pivot bolt 19 of the disk 2 an arm 20 has a rocking support which projects beyond the disk 2 and is acted upon by a 85 spring 21, and to the said arm a pawl 22 is jointed which is in engagement with the ratchet wheel 15. On a second pivot bolt 23 a similar arm 24 has a rocking support which is acted upon by a spring 25, and which carries a pawl 26 engaging in the 90 teeth of the ratchet wheel 18. On a pivot bolt 27 secured to a fixed part of the frame work two shift levers 28 and 29 are mounted which are normally held away from the 95 disk 2 by springs 30 and 31 respectively. The lever 28 is in the path of the arm 20 and the lever 29 in the path of the arm 24.

On a pivot bolt 32 a bell crank lever 33 is mounted which acts on the lever 28, and on a pivot bolt 34 a bell crank lever 35 is mounted which acts on the lever 29. To the free ends of the said levers links 36 and 36' are jointed.

The operation of the mechanism is as 105 follows: The links 36 and 36' are controlled by suitable means such for example as a jacquard card or another counting mechanism. For example, if the link 36 has been drawn to the right as is shown in Fig. 6, 110 the bell crank lever 33 connected therewith forces the shift lever 28 forward and in opposition to the spring 30 and into position for engagement with the arm 20. If now the shaft 1 and the disk 2 are rotated 115 the arm 20 gets in engagement with the shift lever 28 and it is pushed downward thereby, so that the pawl 22 mounted thereon operates the ratchet wheel 15. Thereby the gear wheel 13 as well as the gear wheel 14 are rotated, and the gear wheel 13 which is in mesh with the rack teeth 7 of the disk 4 moves the cam 8 away from the cam 10. As the gear wheel 14 is in mesh with the gear wheel 17 also the gear wheel 16 is rotated 120 which is in mesh with the teeth 9 of the disk 5 carrying the cam 10, so that the said cam is moved in a direction opposite to that of the cam 8. Therefore the increase of the distance of the cams 8 and 130

10 corresponds to the double shifting movement imparted by the pawl 22 to the ratchet wheel.

Whenever the bell crank lever 33 forces the shift lever 28 forward upon each rotation of the shaft 1 the distance of the cams 8 and 10 is increased, so that in the blank being knitted the breadth of the portion which is not being reinforced is enlarged, because the movement of the needle bar causing the increase in the knitting depth ceases at an earlier moment and begins later. If on the other hand it is desired to reduce the portion which is not to be reinforced, the bell crank lever 35 must be moved by the counting mechanism. Thereby the shift lever 29 located in the path of the arm 24 is rocked forward, so that upon rotation of the shaft 1 and the disk 2 the arm 24 is rocked and the pawl 26 mounted thereon acts on the ratchet wheel 18, which carries along the gear wheels 16 and 17. The gear wheel 16 engages in the teeth of the rack teeth 9 of the disk 5 and shifts the cam 10 mounted on said disk toward the cam 8. Simultaneously the gear wheel 17 rotates the gear wheels 14 and 13 and through the latter the disk 4 and the cam 8 mounted thereon, so that now both cams are shifted relatively to each other a distance corresponding to the double path of the ratchet wheel 18.

By providing a jacquard pattern or selector or controlling mechanism of the proper form the beginning and the end of the change of the knitting depth can be varied as is necessary for obtaining the desired form of the reinforced part.

While in describing the invention reference has been made to a particular example embodying the same, I wish it to be understood, that my invention is not limited to the general arrangement and construction of the parts shown in the figures. For example, the mechanism for setting the cams 8 and 10 can be constructed in a different way, and the change of the knitting depth can be performed by other means.

I claim herein as my invention:

1. In an apparatus for making reinforced knitted goods, the combination with the needles, and their operating mechanism, of means comprising coöperating cams mounted on the same shaft for setting the needles according to the desired knitting depth, gear wheels operatively connecting the cams for movement in opposite directions, and automatic means to set said cams in different positions.

2. In an apparatus for making reinforced knitted goods, the combination with the needles, and their operating mechanism, of means for setting the needles according to the desired knitting depth, said means comprising a rotary disk, a pair of cam disks

mounted on said disk coaxially thereof, and gear wheels mounted on the disk and connecting the cams for operation in opposite directions, and automatic means to set said cams in different positions.

3. In an apparatus for making reinforced knitted goods, the combination with the needles, and their operating mechanism, of means for setting the needles according to the desired knitting depth, and means comprising a rotary disk, a pair of cam disks mounted on said disk coaxially thereof, gear wheels mounted on the disk and connecting the cams for operation in opposite directions, and pawl and ratchet mechanism mounted on said disk and adapted to operate the gear wheels for setting the cams in different positions, and automatic operating means for the pawl and ratchet mechanism.

4. In an apparatus for making reinforced knitted goods, the combination with the needles, and their operating mechanism, of means for setting the needles according to the desired knitting depth, and means comprising a rotary disk, a pair of cam disks mounted on said disk coaxially thereof, gear wheels mounted on the disk and connecting the cams for operation in opposite directions, and duplicate pawl and ratchet mechanism mounted on said disk and adapted to operate the gear wheels for shifting the cams one away from and the other one toward each other, and automatic operating means for the pawls and ratchet mechanisms.

5. In an apparatus for making reinforced knitted goods, the combination with the needles, and their operating mechanism, of means for setting the needles according to the desired knitting depth, said means comprising a rotary disk, a pair of cam disks mounted on said disk coaxially thereof, gear wheels mounted on the disk and connecting the cams for operation in opposite directions, and duplicate pawl and ratchet mechanism mounted on said disk and adapted to operate the gear wheels for shifting the cams one away from and the other one toward each other, and automatic, selector controlled operating means for operating the pawl and ratchet mechanisms.

6. In a knitting apparatus, the combination of knitting needles, operating mechanism therefor, means for controlling the knitting depth of said needles comprising a pair of revolute controlling members adapted to assume variable positions relative to each other, and means for varying the controlling positions of said revolute controlling members during the knitting operation, whereby the timing in the change of the knitting depth may be varied in accordance to the pattern to be worked.

7. In a knitting apparatus, the combination of knitting needles, operating mechanism therefor, means for controlling the

knitting depth of said needles comprising a pair of revoluble controlling members adapted to assume variable positions relatively to each other, a pair of operating members one for each of said revoluble controlling members, said pair of operating members being operatively interconnected to actuate said controlling members synchronously in opposite directions, and shiftable driving members for each of said operating members and adapted to be actuated independently of each other during the knitting operation, whereby the timing in the change of the knitting depth may be varied in accordance 15 to the pattern to be worked.

8. In a knitting apparatus, the combination of knitting needles, operating mechanism therefor, means for controlling the knitting depth of said needles comprising a 20 pair of revoluble controlling members adapted to assume variable positions relative to each other, a pair of operating members one

for each of said revoluble controlling members, said pair of operating members being operatively interconnected to actuate said controlling members synchronously in opposite directions, shiftable driving members for each of said operating members and adapted to be actuated independently of each other during the knitting operation, and operative connections in conjunction with each of said shiftable driving members for having said shiftable driving members controlled by a selector, whereby the timing in the change of the knitting depth may be varied in accordance 30 to the pattern to be worked.

In testimony that I claim the foregoing as my invention, I have signed my name in presence of two subscribing witnesses.

FRANZ CECKA.
